UNITED STATES PATENT OFFICE.

NEWTON N. BROWN, OF RACINE, WISCONSIN, ASSIGNOR TO GOLD MEDAL CAMP FURNITURE MANUFACTURING COMPANY, OF RACINE, WISCONSIN, A CORPORATION OF WISCONSIN.

DESIGN FOR A CHAIR LEG.

Application filed February 7, 1927. Serial No. 20,644. Term of patent 14 years.

To all whom it may concern:

Be it known that I, NEWTON N. BROWN, a citizen of the United States, residing at Racine, in the county of Racine and State of Wisconsin, have invented a new, original, and ornamental Design for Chair Legs, of which the following is a specification, reference being had to the accompanying drawing, forming a part thereof.

In the drawing, Figure 1 is a front view of a chair leg showing my new design; and Figure 2 is a side view of the same.

I claim:

The ornamental design for a chair leg as shown.

NEWTON N. BROWN.
